UNITED STATES PATENT OFFICE.

WILLIAM C. F. PAPKE, OF CINCINNATI, OHIO.

DESIGN FOR A PRINTER'S RULE-CORNER.

No. 39,562.

Specification for Design.

Patented Sept. 22, 1908.

Application filed July 22, 1907. Serial No. 385,091. Term of patent 14 years.

To all whom it may concern:

Be it known that I, WILLIAM C. F. PAPKE, a citizen of the United States, residing at Cincinnati, in the county of Hamilton and State of Ohio, have invented a new, original, and ornamental Design for Printers' Rule-Corners, of which the following is a specification, reference being had to the accompanying drawing, forming a part thereof.

In said drawing, Figure 1 is a top plan

view of a printer's-rule corner, showing my new design, and Fig. 2 is a perspective view of said corner.

I claim:

The ornamental design for a printer's-rule corner, as shown.

WILLIAM C. F. PAPKE.
